UNITED STATES PATENT OFFICE

2,639,001

VACUUM CLEANER

Carl E. Meyerhoefer, Brooklyn, N. Y., assignor to
 Lewyt Corporation, Brooklyn, N. Y., a corporation of New York

Application July 29, 1950, Serial No. 176,714

1 Claim. (Cl. 183—37)

1

This invention relates to a structurally and functionally improved vacuum cleaner and in its more specific aspects aims to provide an alternative and improved assembly over that disclosed in United States Patent 2,516,707 of July 25, 1950. It is an object of the invention to provide a mechanism in which under operating conditions a maximum filter area will be exposed. Therefore, the apparatus will function over long periods of time with freedom from all difficulties incident to clogging.

A further object is that of furnishing a structure of this type in which a dirt and dust receiving unit is included such that the operator may bodily remove the unit when the latter is filled with accumulated waste material; such removal being achieved with minimum effort and time expenditures and being moreover capable of accomplishment without substantially any soiling of the hands or clothes. Thereupon a new unit may readily be operatively positioned within the assembly.

Another object is that of furnishing a vacuum cleaner which may have large capacity and in which the dirt, dust and other waste material entrained in the incoming air will be automatically deposited in a suitable receptacle portion before that air passes through the filter. Thus, the surface of the latter will be subjected to only a minimum extent to a clogging action.

Still another object is that of providing the apparatus of this type which will embody relatively few parts each individually simple and rugged in construction, such parts being capable of ready assemblage and when so assembled furnishing a unitary mechanism operating over long periods of time with freedom from all difficulties.

With these and other objects in mind reference is had to the attached sheets of drawings illustrating practical embodiments of the invention and in which:

Fig. 1 is a side elevation of a vacuum cleaner apparatus with certain of the parts shown in section;

Fig. 2 is a bottom sectional plan view taken along the lines 2—2 in the direction of the arrows as indicated in Fig. 1, and with the primary filter removed;

Fig. 3 is a sectional plan view of the supporting ring with the primary filter shown in operative relation with respect thereto;

Fig. 4 is a view similar to Fig. 1 but showing an alternative form of apparatus;

Fig. 5 is a sectional plan view taken along the lines 5—5 and in the direction of the arrows as indicated in Fig. 4; and

2

Fig. 6 is a fragmentary perspective view of a preferred form of removable filter unit as may be utilized in connection with the structure shown in Fig. 4.

Referring primarily to Fig. 1 the numeral 10 indicates the upper housing portion of the assembly which may be provided with a carrying handle 11 which also connects with a cover 12 to permit removal of the latter. This housing may be formed with an annular series of exhaust openings 13 and an actuating treadle 14 for a switch all as taught in the prior United States Patent afore-identified.

As also taught in that patent housing 10 may be provided with an outstanding flange portion 15 bearing upon a gasket 16 preferably of rubber and carried by the upper edge of the lower or tub portion 17 of the assembly. A motor within a suitable casing 18 serves to drive a blower or fan structure 19 by means of which air is drawn through an opening in a side wall of the tub and exhausted through the ports or vents 13. A supporting flange member 20 may extend downwardly from casing 10 and serve to mount a filter. Also extending downwardly from the lower face of the casing assembly is a motor support in the form of brackets or straps 21 to which is secured a plate or ring 22. Layers of spacing and cushioning material 23 may intervene the brackets 21 and the casing portions for the motor and blower wheels and thus serve to support the latter from casing 10. Ring 22 defines a central aperture in line with the intake of the blower wheel casing and through which brackets 21 may be extended downwardly to overlap one another in face to face contact. At this point they may be coupled by a rivet 24 or other suitable securing member which also serves to mount a disc 25.

Referring next to Figs. 2 and 3 in which ring 22 has been shown in some detail, it will be observed that the body of the ring is extended outwardly at a plurality of points and as indicated at 26. Thus a somewhat star-shaped configuration is provided for. Each of the projecting portions is conveniently formed with an outstanding rib 27. A filter may be provided by employing a disc of woven cotton material. The edge of this disc is provided with a seam through which a constricting wire 28 may pass to thus maintain the adjacent edge portions of the filter body fixed and cause that body to assume somewhat the shape of a bag as indicated at 29. The wire 28 is caused to lie within the space defined by flange 20. Under these circumstances and as shown in Fig. 1, the body of the bag passes around the

ends of the projections 26 and in contact with the outer face of disc 25.

With casing portion 10 secured to tub 17 by means of suitable fasteners (not shown) it is apparent that an operator grasping handle 11 may lift the entire assembly as a unit. With those catches released casing 10 will, of course, move upwardly with respect to tub 17 as a lifting force is applied to handle 11. Under those circumstances that casing together with the motor-blower assembly and the filter will shift as a unit. Filter 29 is to be regarded as a secondary filter. A primary filtering action will occur by means of a filter arranged in advance of the same.

Such an advance or primary filter is disclosed in my co-pending application for United States Letters Patent on filter structure, Serial No. 176,715, filed on July 29, 1950. As shown in Fig. 1 it will be in the form of an air pervious bag 30 of suitable paper and having an over-all length preferably not less than the diameter of tub 17. This bag may be provided with an inlet collar 31 formed of cardboard or other suitable material. The base of the tub is provided with any desired number of ribs 33. The intake opening of the tub is defined by an outwardly extending tubular member 32 which by means of protuberances may furnish a convenient coupling such that a hose or other accessory may be readily connected therewith or removed therefrom. In line with the member 32 and extending inwardly of tub 17 is a fitting 34 in the form of a downwardly discharging deflector or nozzle. The external surface of this nozzle is slightly tapered and its maximum diameter may be substantially equal to the internal diameter of collar 31. Also the length of fitting 34 in advance of its mouth portion should be in excess of the height of collar 31. Therefore that collar may readily be slipped over fitting 34 and when in position the mouth of the nozzle will be wholly within the body of bag 30.

Considering the operation of the apparatus as shown in Figs. 1, 2 and 3 it will be understood that casing 10 is primarily removed from tub 17. Thereafter a bag of air porous paper such as 30 is applied to the fitting 34. If desired, the bag may be left in collapsed condition. This will be because when casing 10 is once mounted and the parts are operated, the air rushing in through collars 32 and 31 will serve to distend the bag. So distended and in view of its over-all length the base of the bag will bear against the inner face of tub 17 at a point substantially diametrically opposite the intake opening of the tub. Therefore a reaction force will be set up such that incident to the expansion of the bag, collar 31 will constantly be urged to have its edge portion engaged by the inner face of tub 17 adjacent the base of fitting 34.

At the same time the side wall of the bag which extends adjacent to disc 25 would be forced into intimate contact with the surface of filter 29 substantially throughout the zone of the disc. Otherwise, the bag will generally occupy the position and embody the shape shown in Fig. 1. In such position it will bear against the tub surfaces adjacent the air channels provided by ribs 33. Accordingly with air flowing through those channels substantially entire bag surface will be subject to suction. Accordingly a maximum filtering area will be presented. With air flowing through the assembly the secondary filter provided by cloth 29 will generally assume the shape indicated in dotted lines in Fig. 1. Due to the provision of the projections 26 or generally star-

shaped configuration of ring 22 the filter 29 may not collapse upon itself. Also its operative surface will not include layers overlapped with respect to each other. Rather at all times and even under maximum conditions of suction, the full effective surface of the primary filter will be exposed to the passage of air. Also no parts of the same can be drawn into the suction opening of the blower wheel assembly. With the surface of this filter so exposed any clogging tendencies on the part of dust particles entrained in the air stream will be in effect nullified so that even very infrequent cleaning of the surface of filter 29 will suffice to keep the same substantially dust free.

As it will be understood the assembly is usable for a long period of time before the body of the bag 30 becomes so filled and coated with particles of foreign matter that it is desirable to renew this unit. When such renewal is necessary casing 10 may be lifted from tub 17. Thereupon an operator may simply grasp collar 31 and move the same to clear fitting 34. At this point the dust filled bag may be bodily lifted from the tub and be replaced by a fresh bag. Secondary filter 29 serves under all circumstances to prevent the parts of the blower wheel from being engaged or clogged by filter cloth or paper. Also it serves as an emergency filter unit in the event that an operator attempts to use the apparatus without a bag 30 in position. As afore brought out the projections of ring 22 assure that the complete area of the primary filter is at all times exposed to the passage of air free from any folds or multiple layers. Moreover this ring prevents the use of an improper filtering element in substitution for a bag such as 30 or its equivalent.

In the form of structure shown in Figs. 4 and 5 the same general arrangement of parts supported by the upper casing is present as in the structure of Fig. 1. For this reason the same reference numerals as heretofore employed have been used to designate these several parts. However, in this form of device, the brackets 35 which mount the motor and blower assembly preferably by means of supporting layers 36 are formed with an opening adjacent the lower portion at which they overlap. Through this opening a rod 37 slidably extends. A spring 38 urges the rod 37 downwardly. This rod carries a disc 39 adjacent its outer end; such disc corresponding to the disc 25 as previously described. A latch member 40 may co-act with a groove in rod 37 to retain the latter in retracted position. This latch is conveniently actuated by a Bowden cable connected to the actuator 14 of the switch. Structure similar to this is disclosed and described in my prior application for United States Letters Patent for vacuum cleaner identified under Serial 83,147 and filed on March 24, 1949. Also as taught in that application a spring 42 may normally maintain the latch operatively disposed with respect to rod 37 and a guiding bracket 43 may be provided to assure that the rod shifts in a straight line.

A filter 44 corresponding to filter 29 is likewise mounted in this form of the apparatus by flange member 20. It extends in contact with the outer face of disc 39 and also over the projecting portions 45 of plate 46 corresponding to plate 22 as afore-described. Filter 44 is enclosed in a filter 47 as shown especially in Fig. 6. The latter is conveniently formed of nylon and is provided with a bias bead 48. Enclosed within the latter is a constricting element which may take the

form of a coiled spring 49. The space above the head or wire of filter 44 and provided by the retaining flange assembly 20 is adequate to accommodate the edge portion 48 of filter 47. Therefore this filter may be retained in a position at which it envelops filter 44 but may at the same time be readily removed for purposes of cleaning and renewal.

The tub portion of the assembly includes a relatively deep body 50 to which a base 51 is suitably secured. Enclosing this base is a frame 32 having three or more outwardly projecting platform portions 53. Secured to the underface of the latter are casters 54. The height of the tub portion 50 is such that the inlet nozzle or fitting 55 extends well below the filter assembly. In common with the fitting 34 this nozzle discharges downwardly towards the base of the apparatus.

The operation of this assembly will be similar to that heretofore described in connection with the apparatus as illustrated in Fig. 1. Filter 47 may be renewed and replaced as necessary. Ring 46 and its projections 45 will serve to maintain both filters in position at which their entire effective areas are exposed to the passage of air. When these filters become clogged to a sufficient extent the resistance to the passage of air will cause a retraction of rod 37 against the action of spring 38. Under these circumstances latch member 40 will extend into the groove of rod 37 to maintain the latter and the plate in retracted position. This disposition of the parts will be maintained through to and including that phase of the operation in which actuator 14 is operated to cause a deenergization of the motor. In this connection it will be appreciated that a substantial interval of time will elapse between the opening of the switch and the time when the momentum of the motor and fan diminishes to a point where the suction is no longer effective to maintain the filter and other parts in retracted position. Therefore, with the momentary actuation of the pedal 14 a retraction of the latch will not result in the rod 37 shifting. However, when the parts have once reached a position of rest and actuator 14 is again operated then no air current will be passing through the filter. Accordingly, the instant the switch is closed latch 40 will be retracted by cable 41 and rod 37 together with the parts associated therewith will violently project in an outward direction thus tensioning and snapping the layers 44 and 47 into a taut condition. Accordingly, the particles of dust and dirt adhering to the outer surfaces of these layers will be projected from their faces and the filter units will thus be cleaned.

Incoming air will be diverted as indicated in lines in Fig. 4 downwardly. Therefore with the increase in cross-section area of the tub and the consequent slowing down of the air flow, heavy particles will be deposited upon the surface of

base 51. As shown in Fig. 5 the air flow will—after being diverted by contact with the surface of the base—be generally fan-shaped and also follow the inner surfaces of the tub in separate and opposed paths through substantially 180°. These opposed streams will meet and thus be further slowed down. This will result in an additional depositing of entrained particles of foreign material. Therefore dust, threads and other foreign particles will largely be deposited upon the base of the apparatus and will not have to be separated from the air flow incident to the air passing through the filter assembly 44—47. The air flow occurring in the structure shown in Fig. 1 will be quite similar and modified only due to the configuration of the inner faces of filter 39.

Because of the relatively great height of the tub 50 it is feasible to use the apparatus in the presence of moisture. This would occur where, for example, a rug has been shampooed with suds which are imbedded in its body or its surface. As such suds are drawn through the fitting 55 a maximum suppressing action on the body of the suds will occur. Accordingly they will not tend to readily build up to the level of the filter.

Thus among others the several objects of the invention as specifically afore-noted are achieved. Obviously numerous changes in construction and rearrangements of the parts might be resorted to without departing from the spirit of the invention as defined by the claim.

I claim:

A vacuum cleaner including in combination a housing, a casing for a motor-driven fan carried by and extending beyond said housing, straps connected with said housing and extending below said casing, a flexible filter connected to said housing and loosely enclosing the extended casing portion and straps, a ring-shaped plate extending laterally from and connected to said casing, a series of radially extending arms projecting outwardly from the outer edge of said plate, said straps extending through and below said ring, said plate being disposed within said filter and the projecting arm portions thereof bearing against the inner face of the latter to maintain it in distended condition.

CARL E. MEYERHOEFER.
